UNITED STATES PATENT OFFICE.

CASSIUS M. GAY, OF LOS ANGELES, CALIFORNIA.

GAS-ENGINE.

1,151,455.

Specification of Letters Patent. Patented Aug. 24, 1915.

Application filed September 9, 1913. Serial No. 788,819.

To all whom it may concern:

Be it known that I, CASSIUS M. GAY, a citizen of the United States, residing at Los Angeles, in the county of Los Angeles, State of California, have invented certain new and useful Improvements in Gas-Engines, of which the following is a description, reference being had to the accompanying drawing and to the figures of reference marked thereon.

10 The invention relates to new and useful improvements in gas engines and more particularly to engines of this type wherein a rotary sleeve valve surrounding the cylinder operates to control the intake and exhaust ports.

An object of the invention is to provide a gas engine of the above type with a central working barrel or cylinder in which the piston reciprocates and outside of which the rotary sleeve valve is located, which working barrel or cylinder is supported at its upper or explosive end and hangs free within said rotating sleeve valve.

25 A further object of the invention is to provide an engine of the above character with a water jacket located in said working barrel, which water jacket substantially encloses the combustion chamber within the 30 working barrel.

A further object of the invention is to provide an engine of the above type wherein a plurality of working barrels are mounted in cylindrical housings cast integral with 35 each other and closed by a common cover which serves to hold the working barrels in place supported by the cylindrical housings.

A still further object of the invention is to provide a device of the above character 40 wherein the cover is cast so as to form intake and outlet manifolds which are connected to the water jacket formed in each working barrel.

A still further object of the invention is 45 to provide an engine of the above type wherein the working barrel is provided with an intake and an exhaust port in the side walls thereof and wherein the rotating sleeve valve extends each side of said ports and is 50 provided with an oil sealing channel located each side of said ports to prevent the escape of the gases.

These and other objects will in part be obvious and will in part be hereinafter more 55 fully disclosed.

In the drawings which show by way of

illustration one embodiment of the invention, Figure 1 is a longitudinal vertical sectional view through an engine embodying the improvements. Fig. 2 is a horizontal 60 sectional view of the same. Fig. 3 is a transverse vertical sectional view of the same. Fig. 4 is a view showing certain of the sleeve valves in side elevation and others in section and means for operating the 65 same.

The invention consists, generally, in providing a gas engine which consists of a plurality of cylinders, each of which has a working barrel formed with a water jacket 70 extending throughout the greater length thereof and substantially surrounding the combustion chamber within said working barrel. This working barrel is suspended at its upper or outer end from the cylinder 75 housing and a rotary sleeve valve is disposed between said working barrel and said housing. A piston reciprocates in said working barrel and intake and exhaust ports are connected with said working barrel. 80 The housings for the different cylinders are closed by a cover which is cast so as to provide an inlet and an outlet manifold which is connected with the water jacket in each working barrel. The sleeve valves for the 85 different cylinders are connected together so as to rotate simultaneously, although adjacent valves rotate in reverse directions. These valves are rotated by a gear action with the main shaft.

90 Referring more in detail to the drawings, the engine consists of a main supporting bed or casing 1 in which is journaled the main shaft 2 having the usual cranks formed therein. Mounted on this main casing, as herein 95 shown, are four cylinders, each of which is provided with a piston 3 connected by a piston rod 4' to the respective cranks on the main shaft. Each of these cylinders are in the main similar and a description of one 100 will answer for the other. Each cylinder consists of an inner working barrel 4 which is formed with a flange 5 at its upper or outer end, which flange rests upon and is supported by the cylinder housing 6. The 105 cylinder housings of the different cylinders are cast integral and, therefore, are provided with connecting webs 7. This working barrel 4 is turned so as to form a true cylinder in which the piston reciprocates. 110 The upper end of the barrel is closed except for an opening extending therethrough, in

which is inserted the spark plug 8. The working barrel is also provided with a water space forming a water jacket for the combustion chamber. The space 9 extends entirely about the sides of the working barrel within the range of reciprocation of the piston and also extends over the top of the working barrel so that the combustion chamber in the working barrel is substantially surrounded by this water jacket. Said space 10 is divided by suitable partitions 10 which terminate short of the bottom of the space so that the water for cooling may be supplied at one side of the cylinder, caused to circulate about the same, and pass out from the other side of the cylinder. Each working barrel is provided with an intake port 11 and an exhaust port 12. These ports are formed in the side walls of the working barrel.

Located between the working barrel and the cylinder housing is a sleeve valve 13 which extends above the intake and exhaust ports. Said valve sleeve and cylinder housing are provided with oil grooves 14 and 15 which are disposed above and below the intake and exhaust ports to prevent escape of the gases. The valve sleeve is provided with a single port 16 which is so disposed as to register with first the intake port and then the exhaust port as the sleeve rotates.

The sleeve valve at its lower end is provided with a gear 17 which may be attached thereto in any suitable way. The gears of the sleeves of the adjacent cylinders intermesh and the rotating sleeve valve of the first cylinder is also provided with a beveled gear 18 which meshes with a beveled gear 19 on an intermediate shaft 20 and this beveled gear 19 is formed with a separate gear meshing in turn with a gear 21 splined to the main shaft. As the main shaft rotates, each of the sleeves will be rotated and these gears are so proportioned that the sleeves rotate once for each two complete rotations of the main shaft.

Each rotating sleeve is formed with an annular projecting rib 22 and a grid ring 23 is held between the gear fastened to the sleeve 50 and this annular rib.

The cylinder housings are closed at their upper ends by a cover 24. This cover 24, as clearly shown in Fig. 3, is cast so as to form an intake water manifold 25 and an exhaust water manifold 26. The intake manifold 55 is connected to one side of the water jacket and the exhaust manifold is connected with the other side of the water jacket. This cover is bolted to the cylinder housings by suitable bolts 27 and the cylinder housings are in turn bolted to the bed castings by bolts 28. The intake ports of the cylinders on opposite sides of the center of the engine are adjacent to each other and are connected to an intake manifold 29. The ex-

haust ports are similarly disposed and connected to an exhaust manifold 30.

In order to disassemble the parts, the cover is removed, which exposes the upper end of each of the cylinders. The working barrel in each cylinder may be then removed as it is suspended or supported by the cylinder housing at the outer or explosive end of the cylinder. The cylinder housings may also be readily removed by taking out the bolts 75 which secure the same to the bed of the engine. This exposes the sleeve valves which may also be removed, if desired, by taking out the supporting grid rings.

From the above description it will be apparent that I have provided a multiple gas engine in which each cylinder is provided with a working barrel which incloses and forms the explosive chamber and this explosive chamber is substantially surrounded by a water jacket which prevents the excessive heating of the lubricant used in connection with the rotary sleeve valve. Not only have I provided an engine which is very efficient in action but also one which is very simple in construction and can be cheaply made and readily assembled or disassembled when desired. It is obvious that minor changes in the details of construction and the arrangement of the parts may be made without departing from the spirit of the invention as set forth in the appended claims.

Having thus described my invention, what I claim is:

1. A gas engine including in combination, an engine base, a cylinder housing mounted on said base, a working barrel located in said housing and having a flange at its upper end adapted to rest on the outer end of the cylinder housing, whereby said working barrel is suspended in said housing, said working barrel having intake and exhaust ports formed therethrough, and a water space therein substantially surrounding the explosive chamber, a piston reciprocating in said working barrel, a sleeve valve located between said working barrel and said cylinder housing, said sleeve valve having an annular rib formed thereon adjacent its lower end, a gear attached to said sleeve valve below said rib, a removable grid supported by said engine base and having an annular projecting portion adapted to extend between the rib on said sleeve valve, and a gear attached thereto for rotatably holding said valve connected to said engine base.

2. A gas engine including in combination, an engine base, a cylinder housing removably attached to said engine base and having an open upper end with a seating ledge formed thereon, a working barrel having a projecting flange adapted to engage said seat, whereby said working barrel is suspended from said

cylinder housing, said working barrel being spaced from the cylinder housing and having a water space formed therein substantially surrounding the explosive chamber, a 5 cover for the upper end of said cylinder housing, said cover forming with the outer end of the said working barrel a water space which is joined to the water space in the side walls of said working barrel, said 10 working barrel having intake and exhaust ports, a piston reciprocating in said working barrel, a valve sleeve located between said working barrel and the cylinder housing, a removable grid seated on the engine base, 15 said sleeve valve having a rib projecting out-

wardly therefrom adjacent its lower end, which ribs project underneath the cylinder housing, said grid having a projecting portion underneath said rib on the sleeve valve for supporting said sleeve valve, a gear attached to said sleeve valve at the lower end thereof, and means engaging said gear for rotating the sleeve. 20

In testimony whereof, I affix my signature, in the presence of two witnesses.

CASSIUS M. GAY.
